UNITED STATES PATENT OFFICE.

JOHANN VOEGLI, OF ZURICH, SWITZERLAND.

APPARATUS FOR THE COMBUSTION OF POISONOUS GASES IN BLAST FURNACES.

Application filed July 7, 1921. Serial No. 482,987.

To all whom it may concern:

Be it known that I, JOHANN VOEGLI, a citizen of the Republic of Switzerland, and resident of Zurich, in the Canton of Zurich, Switzerland, have invented certain new and useful Improvements in Apparatus for the Combustion of Poisonous Gases in Blast Furnaces, of which the following is a specification.

10 This invention relates to apparatus of the kind described and illustrated in my prior specification of the Letters Patent No. 1,371,827 according to which the poisonous gases in blast-furnaces and furnaces of 15 mines, produced by the ores, are caused to be combusted and thus rendered harmless. The object of the present invention is to provide a modified and improved construction of apparatus which will be hereinafter more 20 clearly described and shown by reference to the accompanying drawings. In these drawings:

Fig. 1 is a vertical section through the top of a blast-furnace with the apparatus applied, and

25 Fig. 2 shows a section through line A—B in Fig. 1.

According to this improved construction the poisonous gases rising in the blast-furnace are caused to be combusted by means of 30 acetylene burners. The acetylene together with hydrogen is forced under pressure into two pipes 1 and 2 respectively, the said pipes lying in one and the same plane and embracing the blast-furnace 3 and being secured thereto by any convenient device. The outer pipe 2 receives the hydrogen and the inner pipe 1 conducts the acetylene, and both pipes are made to communicate with a 35 double row of burners 4 of which the nozzles 5 project through the brickwork of the blast-furnace into the interior thereof. The disposition is thereby such that the hydrogen flowing through the outer pipe into the

burners carries the acetylene with it, at the 45 same time flowing from the inner pipe to the burners and thence to the interior of the furnace. The ignited mixture issuing from the several oppositely arranged nozzles 5 causes an intense flame which at once combusted all the poisonous gases rising up in the blast-furnace and consequently renders them 50 harmless.

It will be easily understood that, instead of acetylene, benzene may also be used and 55 applied in a manner similar to that described.

And in order to facilitate the mounting and dismounting or repairs of the apparatus described, I arrange a light gallery or platform 6 at a suitable distance below the pipes, the said platform being secured to the structure 3 by means of stays 7 or other suitable means.

Having now fully described my said invention what I claim and desire to secure by Letters Patent is:—

In the herein-described apparatus for the combustion of poisonous gases in blast-furnaces, the combination with two pipes 70 mounted horizontally and near the top of the blast-furnace and embracing the same and serving to receive and conduct hydrogen and acetylene respectively, of a double row of acetylene burners connected to the 75 said pipes and communicating therewith, the nozzles of said burners projecting into the interior of the blast-furnace and being in pairs and oppositely disposed in relation to each other, all substantially as and for the 80 purpose set forth.

In testimony whereof I have hereunto set my hand in the presence of two subscribing witnesses.

JOH. VOEGLI.
